FUEL PUMP

Walter A. Wood, Detroit, Mich.

Application December 9, 1935, Serial No. 53,528
Renewed October 19, 1939

3 Claims. (Cl. 103—40)

The present invention relates to pumps particularly designated to move fluid fuel for automotive internal combustion engines, from the storage tank of the vehicle to the carburetor or charge forming device.

In the conventional vehicle it is customary to locate the fuel tank at the rear and at a somewhat lower level than the carburetor. Further, in order to enable the latter to function properly, it must be equipped with a constant level device such as a float bowl in which a float controls the inflow of liquid fuel. But, because of the usually small capacity of such float bowls, the valve operated by the float is incapable of withstanding very high pressures.

The problems, therefore, confronting the designer of fuel pumps include that of elevating the fluid fuel variable distances, due to the departure of the vehicle from a truly horizontal position, the delivery of such fuel to the carburetor under a pressure less than that required to force open the float controlled valve, and the meeting of the variable demands for fuel by the engine under changing load conditions.

In addition to these problems, there are yet others which cannot be disregarded, and not the least of these is that of insuring against the so-called "vapor lock" which is due to evaporation of fuel in the fluid line and in the pump and the consequent failure of the pump to supply fuel to the carburetor.

Among the objects of the present invention is to overcome the objections to many of the forms of pumps intended to solve the above problems and provide a structure which will deliver a sufficient quantity of fuel under all conditions at such a pressure as will permit an easy, even flow into the carburetor without danger of flooding.

Another object is to overcome the annoying and dangerous "vapor lock" by providing pump-actuating means permitting the location of the pump and other fuel containing parts sufficiently far from the engine and its heat to prevent conduction or radiation of heat to these parts in amounts large enough to cause evaporation of fuel.

Other objects will readily appear to those skilled in the art upon reference to the following description and accompanying drawings in which—

Figure 1 is a longitudinal vertical section through a preferred form of the pump.

Figure 2 is a similar view of a slightly different form of pump and also showing the pneumatic operating means.

Figure 3 is a vertical section of a back pressure

sure regulator of a somewhat different form from that of Figure 1.

Figure 4 is a more or less diagrammatic view indicating the hook up with a carburetor.

Referring particularly to Figure 1, the pump is indicated as comprising a body member 20, provided at one end with an inlet conduit 21, the outer end of which is threaded to enable the connection of suitable tubing (not shown) leading from a fuel tank (also not shown). The inner 10 or other end of conduit 21 opens through a boss 22 to the under face of body 20, the boss projecting substantially centrally of a seat 23 upon which is secured, with the interposition of a gasket 24, a settling chamber 25.

Surrounding the boss 22 and covering the chamber 25 is a screen element 26, this being dished as shown to permit the projection into the upper part of the chamber to some distance, of an outlet tube 27 to thereby form a gas or air 20 filled pulsation cushioning chamber above the liquid in the settling chamber.

The outlet tube 27 from chamber 25 is a part of the inlet conduit 30 for the pump proper and forms a seat for pump inlet valve 31 opening 25 against a spring 32 acting against and guided by a plug 33.

Conduit 30 leads to a pump chamber 35 formed in the pump body, 20, and shown as a concavity on the underside of the body, and over which is secured a flexible diaphragm 36 which, in turn, is covered by a reversely concave cover plate 37 having a substantially centrally located boss 38 into which is secured a tube 39 communicating with a pulsating means such as is shown in Figure 2. Cover plate 37 is also provided with a lateral boss 37a into which is secured a plug 37b having a capillary passage 37c, the purpose of which will be described later. Leading from chamber 35 is a short tube 45 forming a part of 40 outlet valve 47 which is substantially the same as valve 31.

Conduit 46 and its continuations lead to the point of discharge (usually a carburetor) and in order to properly regulate such discharge it is preferred to insert in this conduit a pulsation dampener and also a pressure regulator.

The dampener is indicated at 50 and shown as a small chambered element opening downwardly into conduit 46, while a suitable form of pressure regulator is shown to the right thereof in this figure. This form of regulator consists of a short tubular continuation 51 of conduit 46 having a cross tube 52, closed at one end 53 and flared at the other to produce a fairly large 55

dished flange 54 over which is secured a flexible diaphragm 55 pressed toward conduit 51 by a spring 56 mounted in a suitable cap 57 provided with a small opening 58. The diaphragm 55 5 carries a plug member 60 lying in the cross tube 52 and loosely fitting therein and provided with a circumferential groove 61 arranged to be in line normally with the bore of tube 51. When back pressure develops in the delivery conduit, fluid 10 passes along the plug body to the underside of diaphragm 55 and lifts the latter and, of course, the plug 60, thereby partially or entirely cutting off flow through the conduit, by virtue of the groove 61 being moved out of registry with the 15 passage or bore.

A somewhat different form of back pressure regulator is shown in Figure 3. This form shows a body into which fluid flows from the delivery side of the pump at 46a. This inlet passage is 20 as shown bent at a right angle and counterbored to provide a valve seat 62, the counterbore providing a space for a fluted valve member 63 co-operating with the seat 62 to throttle or stop fluid flow.

25 Also opening into chamber 64 is a tube 67 arranged parallel to the valve counterbore and containing loosely therein a rod 68 having at its lower end a small cross arm or plate 69 serving to maintain the valve 63 within the counterbore 30 and to move it to seating or unseated position in accordance with the movement of the rod 68. This rod 68 is attached at its upper end to a diaphragm 55a which is mounted and operates in the same manner as diaphragm 55 in Figure 1.

35 In this form of regulator, as the back pressure rises in 66 or the parts beyond, the lifting of diaphragm 55a closes the valve 62—63.

In Figure 4 there is shown the relative arrangement of the pump and associated regulator 40 and carburetor, the latter being indicated at C.

Referring now to Figure 2, this shows a pump involving substantially the same elements as that of Figure 1, excepting the back pressure regulator. In this figure, the settling chamber and 45 its associated screen, inlet valve, etc. is the same in form and function as that already described and will be designated as a whole as 25. The same similarity of construction exists in the pump chamber 35, outlet valve 45—47, outlet passage 50 46 and chamber element 50.

The pump body, however, contains a second chamber 75, for convenience located in alignment with pump chamber 35 and of lenticular shape. This chamber 75 is divided by a diaphragm 76, 55 conveniently an extension of the pump diaphragm, and the upper portion communicates through a passage 77 with outlet passage 46.

Coacting with the underside of diaphragm 76 is a valve member 78 which is cylindrical and is 60 provided with an annular groove normally registering, or substantially so, with the passage 39a, to one end of which is connected a tube 39b leading to the pulsator and the other end of which is connected to the pump chamber 35.

65 Valve member 78, as implied, extends across passage 39a and into a tubular boss 79, in which, or a tubular extension thereof 80, it is supported and held against the diaphragm 76 by a suitable spring 81. The valve member 78 preferably fits 70 snugly in its tubular guide so as to effectively valve the passage 39a and, in order to permit free movement, it is necessary to provide for balancing the pressure in the small chamber or space under diaphragm 76 and in the tube 80. This may 75 be accomplished by providing a passageway 78a

connecting the two spaces, either through the member 78 as shown or through the pump body.

This valve member 78 and its associated operating parts serve also as a back pressure regulator in that pressure developing in passage 46 causes depression of diaphragm 76 and thereby moves valve member 78 downwardly so as to throttle or substantially entirely cut off passage of pulsations through passage 39a to the pump chamber.

In this form of pump as well as in the others shown, including Figure 1, already described, pulsations of alternating increase and decrease of pressure are produced in passages 39, 39a and corresponding passages, through their being connected through a suitable tube 39b to a pneumatic pulsator such as is shown in Figure 2.

This device comprises a cylinder 85, flanged as at 86 for attachment to the wall 87 of an engine crankcase adjacent to the camshaft 88. The tube 39b is secured as by a suitable nipple 89 to 20 the closed end of cylinder 85 while the latter is occupied by a piston 90 actuated in its inward movement by a suitable cam 91 on the cam-shaft 88. The outward return of the piston 90 is accomplished by means of a spring 92 acting 25 between flange 86 and a suitable flange or cover plate or both 93 on the projecting end of piston 90.

While the relative proportions of the cylinder 85, tube 39b (bore and length) are not critical, it is necessary that they be such that the piston 30 substantially completely displaces the air from the cylinder 85 into the tube 39b and pump to produce a quite high pressure therein and, conversely, when the piston moves outward, to permit a quick drop to sub-atmospheric pressure. 35 Further, the tube 39b must be sufficiently long to enable the pump to be located away from the engine to avoid undue heating, and of sufficiently large bore to avoid undue internal friction, not, however, so large as to materially reduce the 40 pressure transmitted to the pump diaphragm. Satisfactory results have been obtained with a pump capacity of twenty gallons per hour at 2000 R. P. M. engine speed in using a pulsating cylinder of 1½ inches bore and $\frac{1}{8}$ inch stroke 45 and a tube (39b) of 12 inches in length and with a bore of .112 inch. These dimensions are of course variable to some degree as will be readily recognized.

Tests seem to show that the pressures in the 50 pulsating elements should be substantially maintained, so that if a longer tube 39b is necessary, or desirable, it should be somewhat smaller, though not so small that the higher wall friction interferes with the rapid passage of air.

Mention has been made above of the capillary passage 37c opening from the atmosphere into the air passages of the pumps shown in Figures 1 and 2. This is a very important element of the 55 pump construction and has several important functions.

In one of its functions, this passage acts as a pressure stabilizer or air volume regulator in that it admits air when the average pressure within is 60 below atmospheric and allows escape of air when the average pressure is higher than atmospheric. The capillary dimensions of the passage, however, prevents free passage of air because of the high 65 wall friction and, therefore, the action of the rapid fluctuation of pressure due to the movement of piston 90 upon the pump diaphragm is not materially affected.

A second function of the passage 37c, more or less incidental to the first, is that of ventilation 75

so that no condensation can take place within the air passages.

A third function, applicable particularly to the pump of Figure 2 is that of bleeding the pressure from passage 39a when the valve 78 has closed.

This application is in part a continuation of the subject matter of my copending application, Serial No. 759,135, filed December 26, 1934, on

10 Pumps.

What I claim is:

1. In a liquid fuel pump having a pump chamber, liquid inlet and outlet conduits connected thereto and valves for providing a one-way flow of liquid fuel through such chamber, means for controlling the delivery of liquid fuel through said outlet conduit comprising a valve in said outlet conduit and opening in the direction of fuel flow, an operating stem for said valve, a diaphragm to which said stem is attached in operative relation and which is exposed to the action of fluid in said outlet conduit, a housing chamber for said diaphragm arranged laterally of said conduit and communicating therewith through a passage in which said stem is loosely movable and acts to restrict the passage of fluid fuel into and out of said diaphragm chamber, and spring means tending to force said diaphragm stem and valve toward valve-open position.
2. In a liquid fuel pump having a pump chamber, liquid inlet and outlet conduits connected thereto and valves for providing a one-way flow

of liquid fuel through such chamber, means for controlling the delivery of liquid fuel through said outlet conduit comprising a valve for said outlet conduit, an operating stem for said valve, a diaphragm to which said stem is attached in 5 operative relation and which is exposed to the action of fluid in said outlet conduit, a housing chamber for said diaphragm communicating with said outlet conduit through a passage in which said stem substantially fills the passage and is 10 loosely movable therein to permit restricted flow of fluid into and out of said chamber around said stem, and spring means tending to oppose the action of said fluid upon said diaphragm.

3. Means for controlling the pressure of liquid 15 fuel delivered from a liquid fuel pump, said means consisting of a passage receiving such fuel, a valve in said passage and regulating flow therethrough, said valve having a stem, a chamber communicating with said passage, said stem being 20 located in and substantially filling said communication but with sufficient clearance to permit restricted movement of fuel into and out of said chamber, a diaphragm mounted in said chamber and operatively attached to said stem, said dia- 25 phragm being exposed on one side through said communication to fluid fuel pressure in said conduit and on the other to atmospheric pressure, and spring means arranged to oppose the action of said fluid pressure upon said diaphragm. 30

WALTER A. WOOD.
